UNITED STATES PATENT OFFICE

2,500,074

WINDOW CURTAIN

Violet Krahling Hill, Summit, N. J.

Application December 8, 1948, Serial No. 64,079

6 Claims. (Cl. 160—123)

1

This invention relates to window curtains, or the like, and particularly to the construction of such curtains in sectional form.

An object of the invention is to provide a curtain made up of a plurality of sections which are removably attached together along horizontal lines.

Another object is to provide such a curtain in which two standard types of sections may be combined to meet widely varying conditions of use and to give a variety of artistic effects.

A further object is to provide certain improvements in the form, construction and arrangement of the several parts, whereby these and other advantages may effectively be attained.

A practical embodiment of the invention is shown in the accompanying drawing wherein

Fig. 1 represents a front elevation of a curtain made up from two sections, as used on a short window;

Fig. 2 represents a front elevation of a curtain made up from three sections, as used on a longer window;

Fig. 3 represents a front elevation of a pair of three-section curtains, as used on a window or group of windows wider than that shown in Fig. 2;

Fig. 4 represents a front elevation of the back member of a top curtain section;

Fig. 5 represents an end elevation of the back member viewed from the right of Fig. 4;

Fig. 6 represents a front elevation of the front (ruffle) member before it is ruffled and assembled with the back member;

Fig. 7 represents a front elevation of the assembled top curtain section;

Fig. 8 represents a vertical section, taken on the line VIII—VIII of Fig. 7, and

Fig. 9 represents a front elevation of a lower curtain section, part of the ruffle being broken away and one corner of the back member being turned over.

Referring to the drawing, the top curtain section is shown as being made by cutting, for instance, a 26" piece of material 1; turning back one cut edge about 3" and stitching it along the lines 2 and 3 to form a heading, with a rod pocket 4; turning the bottom cut edge to form a narrow hem 5, and stitching to the hem 5 a tape 6 bearing fastening elements 7, shown as female snap fastener elements. The front ruffle 8 may be made by cutting two 19" pieces of material 9, 8; sewing them together along the line 10 to form a double-width piece; preferably putting a very narrow hem around the sides and bottom; gather-

2

ing the top to a width equal to that of the back member 1, and stitching the gathered edge 11 to the back member along, or just below, the line 3.

The lower curtain section (Fig. 9) comprises a back member 12, the top cut edge of which is turned, and to which is stitched a tape 13 bearing fastening elements 14, shown as male snap fastener elements; the bottom cut edge being provided with a tape 15 and fastening elements 16 as described in connection with the corresponding part of the top curtain section. A front ruffle 17 is made like the ruffle 8 and is stitched to the lower curtain section along its top edge, as shown.

For use as "glass curtains" the material may be light and more or less transparent, such as organdy, batiste or a fine net, the front and back members being either of the same material or of different materials depending on the effect desired. Other suitable fabrics or combinations of fabrics can be used if the construction shown is to serve other drapery purposes to which it is obviously well adapted.

Figs. 1, 2 and 3 show three of the many possible arrangements of the sectional curtains described herein. In Fig. 1, a relatively short window is covered by a top section 18 (made according to Figs. 4-8) and one lower section 19 (made according to Fig. 9), the fasteners 14 of the lower section being snapped to the corresponding fasteners 7 of the top section. In Fig. 2, a longer window is covered by adding to the sections 18 and 19 another lower section 19a, the fasteners 14 of the latter being snapped to the corresponding fasteners 16 of the section 19. In Fig. 3, two curtains (made up as in Fig. 2) are compressed more tightly toward the sides of a window or group of windows, leaving a space in the middle; the top of this space may be occupied, if desired, by an additional top section 18 or by a valance section, which is like section 18 but without the fastener tape.

The fastening elements for holding the sections together are shown as snap fasteners, which are quite convenient to use and are available in tape-mounted form. Other fasteners, such as hooks and eyes could be substituted with no loss of convenience, and in some cases buttons and button-holes may be suitable.

It is intended that the curtain sections described above should be made up in a limited number of standard lengths, so that a store need only have in stock, for instance, three lengths of top sections and three lengths of lower sections in order to meet demands for nine different lengths of two-section curtains and many more

different lengths of three-section, or longer, curtains. The purchaser may buy as many sections as desired for attaining the necessary length and fullness, and at any time a single section can be purchased to replace one that has become damaged. Where two or more lower sections are used (e. g., Figs. 2 and 3) they can be interchanged from time to time, to distribute the wear which is generally greater near the bottom and sides of a curtain.

There are also important advantages in laundering such sectional curtains. If the bottom section becomes soiled in use, or if any section is accidentally spotted, the single section can be removed and laundered. The curtains can be washed cleaner when handled in small sections, and such sections are not likely to trail on the ground when hung to dry. The top sections can be ironed first and returned to the rod, where they are ready to receive the lower sections as soon as the latter are ironed, thus eliminating all the danger of wrinkling that is encountered in trying to iron and hang long one-piece curtains.

What I claim is:

1. A sectional curtain of the character described comprising, a top section having a back member, a heading, a front ruffle member permanently secured to the back member adjacent the heading and a row of fastener elements secured to the back member along its bottom edge, and a lower section having a back member, a front ruffle member permanently secured to the back member adjacent its top edge and a row of fastener elements complementary to the first named fastener elements also secured to the back member adjacent its top edge.

2. A sectional curtain according to claim 1 in which the first mentioned row of fastener elements is on the front of its back member, and the second mentioned row of fastener elements is on the back of its back member.

3. A sectional curtain according to claim 1 in which the back member and ruffle of the top section terminate downwardly at approximately the same horizontal level, and the back member and ruffle of the lower section likewise terminate downwardly at approximately the same horizontal level.

4. A sectional curtain of the character described comprising, a top section having a back member, a heading, a front ruffle member permanently secured to the back member adjacent the heading and a row of fastener elements secured to the back member along its bottom edge, and at least two lower sections each having a back member, a front ruffle member permanently secured to the back member adjacent its top edge, a row of fastener elements also secured to the back member adjacent its top edge and a row of fastener elements secured to the back member along its bottom edge.

5. A sectional curtain according to claim 4 in which the first and third mentioned rows of fastener elements are on the front of the respective back members, and the second mentioned row of fastener elements is on the back of its back member.

6. A sectional curtain according to claim 4 in which the back member and ruffle of the top section terminate downwardly at approximately the same horizontal level and the back member and ruffle of each lower section likewise terminate downwardly at approximately the same horizontal level.

VIOLET KRAHLING HILL.
